UNITED STATES PATENT OFFICE

104,429

DESIGN FOR A CLIP

Charles Adler, New York, N. Y.

Application March 30, 1937, Serial No. 68,473

Term of patent 3½ years

To all whom it may concern:

Be it known that I, Charles Adler, a citizen of the United States of America, residing in Manhattan, county and State of New York, have invented a new, original, and ornamental Design for a Clip, of which the following is a specification, reference being had to the accompanying drawing, forming part thereof, wherein,

I claim:

The ornamental design for a clip, substantially as shown.

CHARLES ADLER.
